BY

Philip S. McLean
ATTORNEY

UNITED STATES PATENT OFFICE.

MARIE CATHERINE STEICHEN, OF NEW YORK, N. Y.

PERMANENT HAIR WAVING.

Application filed June 9, 1923. Serial No. 644,332.

To all whom it may concern:

Be it known that I, MARIE CATHERINE STEICHEN, a citizen of the United States, and a resident of New York city, county and State of New York, have invented certain new and useful Improvements in Permanent Hair Waving, of which the following is a specification.

The objects of this invention are to produce in permanent form a hair wave of the Marcel type, as distinguished from the coils or curls produced by permanent wave apparatus now in use and further, to effect this desired result in a simple, practical manner.

For the attainment of the objects set forth I have designed a form for the waving of the hair which is of special novel construction, as will be clear from the accompanying drawing, which illustrates an embodiment of the invention in practical, concrete form.

Figure 1 in the drawing referred to is a front or face view of a preferred example of my new hair waver.

25 Figures 2 and 3 are end views of the same.

Figures 4 and 5 are corresponding views of a modification.

The form first illustrated consists of a stem or shank 5, tapered from one end to the other and carrying a series of branches 6 projecting in staggered relation from opposite sides of the stem and terminating in hooks or points 7 standing in approximate parallelism to the same.

35 The ends of the stem are shown as slotted at 8 and 9 to receive thread or the like for temporarily securing the ends of a strand of hair in place.

The preferred method of using the device is to wrap a lock of hair about the base or heavier end of the stem and to then twine the lock under and over the projecting prongs or hooked branches, back and forth across the stem as indicated at 10, until the

45 upper end of the stem is reached, whereupon the end of the lock may be caught by wrapping about the end of the stem and secured by a thread engaged in the slot 9.

The hair thus interlaced over the form is 50 then baked usually by placing a pad about

the form and then slipping an electric heater over the covered form. After a sufficient period, usually about ten or fifteen minutes, the heater is removed and the hair is untwined from the form. The interlacing of the hair across the stem and about the prongs of the form imparts a series of "ripples" or waves to the hair corresponding in effect to the well-known Marcel type of wave, which are made permanent by the baking operation described.

55 The form or waver may be made of aluminum since that is light, inexpensive and capable of standing the heat, but it will be understood that other metals or materials which will answer the purpose, may be employed.

60 The modified form of the invention illustrated differs from that first described, particularly in that the stem is swelled or increased in diameter intermediate the ends of the same, as indicated at 11, and the branches or prongs are staggered in a radial series about the stem. This construction enables the lock of hair being interlaced in a series of loops extending circumferentially about the stem and the swelling of the stem imparts additional curvature to the hair, giving a very pleasing effect.

65 What I claim is:

A form for producing a Marcel wave, comprising a substantially round and straight stem having substantially round tapering branches projecting from diametrically opposite sides of the same and terminating in abruptly curved hooks, said hooked branches forming substantially right angled curved bends relative to the stem to enable a strand of hair being caught within the curve of the hooks and interlaced back and forth across the back of the straight stem and said stem having a substantially round continuation of the same extended beyond the last hooked branch to provide a terminal for the end of the strand of hair to be wrapped about.

70 In witness whereof, I have hereunto set my hand this 4th day of June, 1923.

MARIE CATHERINE STEICHEN.
